CLAIM

The ornamental design for a "percussive massage device," as shown and described.

DESCRIPTION

FIG. 1 is a front perspective view of a percussive massage device, showing our new design;

FIG. 2 is a rear perspective view thereof;

FIG. 3 is a left side view thereof;

FIG. 4 is a right side view thereof;

FIG. 5 is a rear view thereof;

FIG. 6 is a front view thereof;

FIG. 7 is a bottom view thereof; and,

FIG. 8 is a top view thereof.

The broken lines in the drawings are for the purposes of illustrating portions of the percussive massage device, which form no part of the claimed design.

1 Claim, 4 Drawing Sheets---
